UNITED STATES PATENT OFFICE.

EDWIN L. ROBERTSON, OF NEW YORK, N. Y.

RUBBER HEEL.

1,301,974.

Specification of Letters Patent. Patented Apr. 29, 1919.

Application filed June 20, 1918. Serial No. 241,650.

To all whom it may concern:

Be it known that I, EDWIN L. ROBERTSON, a citizen of the United States, residing at the city of New York, in the county of New York and State of New York, have invented certain new and useful Improvements in Rubber Heels, of which the following, taken in connection with the accompanying drawings, is a specification.

10 The invention relates to heels for boots and shoes; and the improvement consists in providing a metallic cup and crowding a sectional rubber heel thereinto so that said cup shall retain the same, said cup being attached to the boot or shoe sole before the insertion of the rubber heel, one of the sections of said rubber heel being cylindrical or having a cylindrical portion so that it may be removed from the cup and said cylindrical portion turned a sufficient distance to present a new wearing surface at the rear of said heel where it usually wears first to thereby preserve a substantially level surface on the bottom of the rubber heel, said 25 rubber heel projecting below said metal cup; and the invention consists in the novel features and combinations hereinafter set forth and claimed.

In the drawings, Figure 1 is an elevation 30 of the rear portion of a shoe with the heel in section showing a rubber heel inserted in a cup shaped like a heel and attached to the rear portion of the shoe sole. Fig. 2 is a bottom plan view of the two-piece rubber heel within the metal cup, the cylindrical portion being at the rear in order to turn the same to present a fresh wearing surface; and Fig. 3 is a bottom plan view of the two parts of the rubber portion of the heel re- 35 moved from the metal cup showing the shape of each part; and Fig. 4 is a bottom plan view of the preferred manner of making and vulcanizing the two-part rubber heel, showing in dotted line the cuts to be made in the rubber after vulcanizing, there- 40 by making a pair of rubber heel portions in one piece, the cut edges being covered by adjacent parts so as not to expose the same; and Fig. 5 is a plan view of the heel shaped 45 cup showing the openings in the bottom of the same for attachment to the shoe sole.

Like characters of reference refer to corresponding parts in the several views.

The numeral 15 designates the shoe which has a sole 16 to which the heel 17 is attached 55 preferably by means of nails 18 which may be clenched within said sole 16.

The heel 17 consists of a metallic cup 19, which is preferably shaped in the regular heel form, and has an opening which enlarges inwardly, that is, toward the bottom of said cup so as to more perfectly retain the rubber or elastic portions 20 and 21 of the heel when they are crowded into the 60 cup 19 and more perfectly preserve the heel shape. The cup 19 has a number of openings 22 in the bottom through which the nails 18 are inserted in attaching to the sole 16 of the shoe. The sides of the cup 19 extend downwardly to within about an 65 eighth or three-sixteenths of an inch of the bottom of the rubber filling parts 20 and 21, that is, said rubber filling parts 20 and 70 21 extend from about an eighth to three- 75 sixteenths of an inch below the lower edge of the metallic cup 19 so as to present a strong rubber tread wearing surface for the heel without contacting the lower edge of the cup at each step.

When the heel wears down to the edge of the cup, the cylindrical rubber portion 20 is removed from the cup 19 and turned sufficiently to obtain a new level wearing surface for said rear or other portion, since most wearers of foot gear wear their heels at the rear side. This presents an entirely new surface in place of said worn side and thus gradually wears all portions of the heel alike thereby greatly prolonging the life of the 80 heel.

In order to rotate the rubber wearing portion of the heel and preserve its shape it must have the round portion at the rear side. Accordingly, said rubber part is preferably made as shown in Fig. 4 and cut through the center to form two heels as shown at 25 and having the semi-circular cuts 26 to form the round rear portions. The two portions 20 and 21 compress 85 against one another and are sufficiently large to necessitate crowding into the cup 19 which cup as hereinbefore stated is preferably smaller at the mouth than within the same so that treading upon the rubber portions constantly crowds them into the rubber cup. Accordingly they do not need attach- 90 95 100 105

ment within said cup though such attachment would not necessarily depart from my invention.

It is apparent that this simple and convenient rubber heel may be made at low cost and has great strength and longevity. The cups may be struck up from sheet metal by suitable dies. The rubber fillers may be molded and cut to shape, as shown in Fig. 4, and the cups and rubber parts may be packed ready for attachment and assemblage on the shoe sole.

I claim as new:

1. A cushion boot and shoe heel comprising a heel shaped cup attached inverted to the sole of said boot or shoe through the bottom thereof, a rubber filler for said cup composed of a cylindrical rear portion and a portion shaped to fit in the front portion of said cup and around the front section of said rear portion, said filler portions sufficiently larger than said cup to be compressed thereinto by pressure to hold the same and extending a spaced distance below the same to provide a cushion tread.

2. A cushion boot and shoe heel comprising a heel shaped cup struck up from sheet metal having a plurality of holes through the bottom of the same, said cup inverted and attached to the sole of the shoe by clenched nails through said holes, a rubber cushion portion slightly larger than said cup compressed thereinto by pressure to hold said rubber cushion portion, said rubber cushion portion extending a spaced distance below the lower edge of said inverted cup to provide an elastic tread for said heel and composed of a cylindrical rear part and a second part shaped to fill the front portion of said cup and fit around the front of said cylindrical rear part to permit removal of said rubber cushion and the change of said cylindrical rear part to present a new level wearing surface at the rear of the heel, and

45 a lift shaped to fit within the bottom of

said inverted cup to give further extension of said rubber cushion portion when the same becomes worn.

3. In an elastic boot and shoe heel, a cup having a semi-circular wall and a straight wall, and a resilient heel member composed of a main cylindrical part and a filler, the main part fitting against said semi-circular wall and the filler having a concave portion fitting against the remainder of the main part and a straight portion fitting against the straight wall of the cup.

4. In an elastic boot and shoe heel, a compressible rotatable main member, a compressible non-rotatable filler member abutting the main member, and means engaging the outer walls of each of said members to attach same to the sole of the boot or shoe.

5. In an elastic boot and shoe heel, a compressible cylindrical member, a compressible filler member, and a cup receiving both of said members.

6. In an elastic boot and shoe heel, a reversible and compressible main member, a compressible filler member, and means engaging the outer walls of each of said members to attach same to the sole of the boot or shoe.

7. In an elastic boot and shoe heel, a reversible compressible main member, a compressible filler member and a cup removably receiving both members.

8. In an elastic boot and shoe heel, a cup, and a sectional heel therein, each of the sections being compressible and meeting in a surface which is approximately normal to the tread surface of the heel.

In testimony whereof I have affixed my signature in the presence of two witnesses.

EDWIN L. ROBERTSON.
